TROPHY

Arthur J. Lorden, North Attleboro, Mass., assignor to the United States of America as represented by the Secretary of the Navy

Application November 1, 1955, Serial No. 38,682

Term of patent 14 years

(Cl. D29—23)

Fig. 1 is a front elevational view of a trophy showing my new design;

Fig. 2 is a rear elevational view thereof; and

Fig. 3 is an edge view thereof.

I claim:

The ornamental design for a trophy, substantially as shown.
